DISPLAY DEVICE

Elmer W. Ericson, Chicago, and Rudolph E. Brauer, Riverside, Ill., assignors to The Barrett Bindery Co., Chicago, Ill., a corporation of Illinois

Application January 29, 1943, Serial No. 473,948

10 Claims. (Cl. 35—53)

This invention relates to display devices and has to do with a display panel simulating in appearance a shingle roof or analogous structure.

The present practice in selling roofing is for the salesman to be provided with panels or folders mounting several or more full size shingles such as are to be used for roofing. These panels or folders are bulky and objectionably heavy, weighing from twenty-five to fifty pounds each, which renders it difficult for the salesman to carry these samples about with him. Further, if the shingles have a rough or granular surface, as is quite common, there is the risk that in displaying the shingles in the home of the prospective purchaser of roofing, furniture and floors will be scratched. However, there is a further and more serious objection, in that it is difficult for the prospective purchaser to visualize from such panels the actual appearance of a roof constructed from the shingles of the samples submitted. The shingles as laid up in a complete roof may have quite a different appearance than that visualized by the purchaser from the panels submitted for his inspection, with the result that the purchaser may be disappointed and dissatisfied with the appearance of the roof. Ordinarily, a roof is viewed from a distance so that the shingles of a shingle roof appear considerably smaller than their actual size. The result of that is that the shingles are not seen individually, but blend together and the roof is viewed in its entirety, as a complete unit or pattern, and it is the appearance of that pattern as a whole which is depended upon to appeal to the eye of the observer. If, on the other hand, a shingle roof or analogous structure be viewed from a short distance, the individual shingles or like elements of the structure are seen as independent parts of the structure, the composite pattern effect is destroyed and the roof has quite a different appearance from that which it presents when viewed from a distance, as is normally the case. Accordingly, in order to obtain the proper effect and convey to the observer the appearance of a proposed shingle roof or analogous structure as laid up, in a display device which is to be viewed close up or at a short distance, the shingles or analogous elements of that device should be smaller than the corresponding elements in the actual structure itself, preferably of a size approximating the apparent size of such elements when that structure is viewed from a distance. In that manner the pattern effect is retained, and the prospective purchaser of shingles or analogous elements can obtain from such a display de-

vice a reliable indication of the appearance of a roof or like structure laid up with full size shingles or analogous elements corresponding to those of the display device.

5 Our invention is directed to the production of a display panel closely simulating in appearance a complete side of a roof or analogous structure as laid up with the sample shingles or analogous elements submitted to the prospective purchaser. 10 Such a panel could be constructed, in theory, by properly assembling and securing together miniature shingles in overlapping relation as laid up in the roof, but constructing a panel in that manner would be time consuming and would render the cost of the panel objectionably high. More specifically, our invention is directed to a panel of the character first above stated in which the elements simulating the shingles are not disposed in overlapping relation but have their end and lower edges exposed to view in such manner as to simulate closely the exposed areas of the shingles of a shingle roof. That renders it possible to produce a display panel closely simulating in miniature one side of a shingle roof and which 15 is of light weight, occupies comparatively little space and can be produced at relatively low cost. Further objects and advantages of our invention 20 will appear from the detail description.

In the drawing:

30 Figure 1 is an elevational view, partly broken away and in section, of a pair of opposed dies with the base member and the facing member disposed therebetween in superposed registering relation, with the dies closed and pressing the base member and the facing member together;

35 Figure 2 is a face view of the panel produced by the pressing operation of Figure 1, after it has been trimmed;

40 Figure 3 is a sectional view taken substantially on line 3—3 of Figure 2, on an enlarged scale; and

45 Figure 4 is a sectional view taken substantially on line 4—4 of Figure 2, on an enlarged scale.

The display panel of our invention comprises a base member and a facing member, as previously noted. The base member, indicated generally by the reference number 15, is formed from a rectangular sheet of what is known as a double thick black buckeye cover paper, or any other suitable material, which sheet is formed to desired shape by suitable embossing dies. Base member 15 comprises a top strip 16, which is not embossed, and a plurality of mounting elements 17. When making up a display panel of square tab shingles, the mounting elements 17

are rectangular in shape and are disposed in rows lengthwise of base member 15 with the elements of each row spaced apart at their ends by narrow grooves 18, provided by channel elements 19 offset rearwardly of member 15. The elements 17 of each row are staggered relative to the elements of the next adjacent row, the upper edges of the elements 17 of the top row are at the lower edge of strip 16, the upper edges of the elements 17 of each of the other rows are respectively at the lower edges of the elements of the next superjacent row, and elements 17 extend downward and forward of base member 15. The mounting elements 17 correspond to the exposed areas of the shingles of a square tab shingle roof and are of the same proportions as the exposed areas of the full sized shingles, accurately reproducing the exposed areas of the latter in miniature or on a reduced scale.

The base member 15 receives a facing member 20, which may be formed of the same kind of material as base member 15 but preferably is somewhat heavier or thicker than the latter member. This facing member 20 comprises a flat sheet of material 21 one face of which is provided, for the major portion of its area, with a coating 22 of a granular mineral material which may be of any suitable or desired available color, this coating being applied in a known manner, in the same manner as a granular coating is applied to asphalt shingles, or in any other suitable known manner. The particles or granules of coating 22 are, of course, much finer or smaller than the granules of the coating applied to a full size shingle and are so graded or of such size that coating 22 closely simulates in appearance, in miniature, the finish of the full size shingles. Coating 22 may terminate a short distance from the upper edge of sheet 21, leaving a top strip 23 of appreciable width which is uncoated.

The member 20 is then cut, conveniently by means of a suitable die, to provide a plurality of rectangular facing elements 24 arranged in rows lengthwise of sheet 21 and spaced apart at their ends by narrow spacing strips 25 with the strips of each row cut at their upper ends and connected at their lower ends to the facing elements of the next subjacent row, there being a coated area or strip 27 at the lower portion of top strip 23 which is uncut. The cutting edges of the die may be provided with nicks for leaving relatively narrow uncut strips connecting together the otherwise cut apart elements of the facing member 20, or the cutting die may be adjusted so as not to cut completely through member 20, leaving approximately 10% of the thickness thereof uncut. Preferably, we use the latter method. That leaves the elements of the cut member 20 connected together by a thin layer of fibres of the paper, sufficiently strong to hold such elements together during subsequent handling of the cut facing member 20 but of a character to be readily broken or torn apart when the elements of member 20 are relatively displaced under appreciable pressure. Facing member 20, thus cut, comprises facing elements 24 spaced apart endwise by the restricted relatively narrow spacing strips 25, the elements 24 and the spacing strips 25 corresponding in shape and size and arrangement to the mounting elements 17 and grooves 18 of the base member 15 and being connected together by the relatively thin uncut portions of member 20, as above.

The base member 15, formed as above disclosed, is placed upon the upper face of a supporting die

30, shown in Figure 1, and the facing member 20 is then placed upon the upper or forward face of base member 15 in register therewith, with spacing elements 24 in register with the forward 5 faces of elements 17 and spacing strips 25 in register with grooves 18, of member 15, there being an intervening film of adhesive between the base member 15 and the facing member 20, provided by coating either the forward face of 10 base member 15 or the back of member 20, preferably the latter, with a suitable adhesive. After the members 15 and 20 have thus been disposed in superposed relation and in proper register, they are pressed tightly together by means of an 15 upper die 31 opposed to the lower die 30. The pressing face of die 31 conforms substantially to the upper or forward face of base member 15, having elements corresponding to the mounting elements 17 and other elements corresponding to 20 the grooves 18 and to the strips 25, for displacing the latter rearward out of the plane of sheet 21 and depressing them into the grooves 18. As a result of this pressing operation, elements 24 of member 20 are separated from each other and 25 from the upper ends of spacing strips 25 and the base member 15 and the facing member 20 are secured together, by means of the adhesive, with elements 24 seating flat upon elements 17 and the spacing strips 25 pressed into the grooves 18 30 rearward beyond the facing elements 24 and exposing the side edges thereof. Since the facing elements 24 are secured flat upon the mounting elements 17 and are inclined therewith downward and forward of the base member 15, the lower 35 edges of elements 24, as well as the side edges thereof, are exposed to view, the result being a panel which, in its finished and trimmed condition shown in Figure 2, closely simulates in appearance a square tab shingle roof in miniature. 40 The finished panel preferably retains the top strip 23 of facing member 20 and the underlying top strip 16 of base member 15, for convenience in mounting the panel in a holder if desired, for which purpose the panel may be provided, adjacent its upper edge, with a row of suitably spaced openings 28. The panel constructed in this manner is of light weight, may be produced at small cost and occupies but little space, while presenting the appearance of one complete side 45 50 of a square tab shingled roof in miniature, sufficient to enable the prospective purchaser to visualize clearly the appearance of a roof constructed of shingles of full size represented by the elements of the panel and thus more quickly decide on the purchase.

While we have referred to the facing member 20 as being provided with a coating 22 of granular material, that is not essential to the broader concepts of our invention, which comprehends 60 forming the facing member 20 of any suitable material presenting an exposed surface simulating the surface of the shingles which it is desired to sell, which shingles may be formed of various materials and may vary widely in appearance.

We have illustrated and described our invention as embodied in a panel of square tab shingles, by way of example. Shingles may vary widely in shape as well as in finish and color effect, as is well known. Our invention is well 70 suited for producing panels simulating shingles of any desired shape or type and comprises the broad principle of embossing a base sheet or member to provide mounting elements and securing the shingle elements of the facing member on the mounting elements, the parts being so

disposed and related that the appropriate edges of the shingle elements are exposed to view in a manner to produce the desired shingle effect.

It will be understood, from the above, that our invention is well suited for producing panels simulating various types of shingle roofing. Since there is a large variety of shingles, it is neither practicable nor desirable to attempt to illustrate and describe in detail panels depicting each type. In that connection, it is thought that the detailed disclosure with respect to the panel of Figure 2 will suffice, it being understood that panels simulating other types of shingle roofs are made in the same manner, except that the embossment of the base member and the cutting of the facing member are varied in detail to suit the particular type of shingle roofing which it is desired to simulate. Briefly, our invention comprises embossing a base member to provide it with a plurality of mounting elements disposed in generally stepped relation, cutting a facing member to provide a plurality of facing elements of the desired size and shape, and securing the facing elements upon the outer faces of the mounting elements, producing the desired shingle effect.

The base member may be embossed and the facing member mounted thereon in two separate operations, as above described, or in a single operation. In the latter case, the base member, in its unembossed condition, and the facing member, appropriately marked or cut, are disposed in superposed relation and in proper register, with a film of adhesive between them. They are then placed between appropriate dies, which are then closed and serve to emboss the base member and to relatively displace and more or less separate the elements of the facing member so that the latter elements are mounted upon the correspondingly embossed elements of the base member, in substantially the manner above described. The pressure exerted by the dies also serves to press the embossed elements of the base member and the elements of the facing member together, so that they are firmly secured together by the adhesive. In that manner, the embossing of the base member and the mounting thereon of the facing member is accomplished in a single operation. When doing that, the sheet of material for the base member preferably is somewhat thinner and softer, and the recesses and projections of the dies are of somewhat greater depth or height, than when the base member is embossed separately and the panel is formed in two operations in the manner previously described. With that explanation, Figure 1 may be taken as also illustrating how a panel embodying our invention is produced in a single operation, in the manner explained.

When the panel is produced in a single operation, a backing sheet may be applied to the panel, for imparting increased strength and rigidity thereto, by placing the backing sheet upon the exposed surface of the base member, with one or both of the opposed surfaces thereof coated with a suitable adhesive, and subjecting the assembly to pressure between the dies, sufficient to emboss the backing sheet and press the embossments thereof firmly into the embossments of the backing member. In either case, that is, whether the panel is formed in two operations or in a single operation, one or more backing sheets may be applied to the panel, if desired, in the manner described or in any other suitable manner.

We have described our invention, by way of

example, as applied to a panel simulating a shingle roof, to which, in its more specific aspects, it is particularly suited. It is to be understood, however, that it is not limited in that respect.

- 5 5 We contemplate, within the broader aspects of our invention, the production of panels or analogous structure simulating a shingle roof, siding, or any other structure of the same general character comprising shingles or other elements intended to be arranged in more or less overlapping relation with edges thereof exposed to view. Accordingly, the term "shingle" as used herein is to be construed as meaning either a shingle, within the generally accepted meaning of that term, or any other element intended to be associated with other like elements in more or less overlapping relation with edges thereof exposed.

10 20 As above indicated, and as will be understood by those skilled in the art, variations may be resorted to in carrying out our invention without departing from the field and scope thereof, and we intend to include all such variations, as fall within the scope of the appended claims, in this application in which the preferred forms only of our invention have been disclosed.

25 We claim:

1. A panel simulating in appearance a shingle roof in miniature, said panel comprising elements cut apart from each other and corresponding to and simulating the exposed areas of the shingles of a shingle roof and arranged in substantially non-overlapping relation extending downward and forward of said panel with their side and lower cut edges exposed to view.
- 30 35 2. A panel simulating in appearance a shingle roof in miniature, said panel comprising elements cut apart from each other and corresponding to and simulating the exposed areas of shingles of a shingle roof and arranged in substantially non-overlapping relation with the lower ones of said elements respectively extending downward and forward of said panel from the lower edges of the next superjacent elements with their side and lower cut edges exposed to view.
- 40 45 3. A panel simulating in appearance a shingle roof in miniature, said panel comprising elements cut apart from each other and corresponding to and simulating the exposed areas of shingles of a shingle roof and arranged in substantially edge-to-edge and non-overlapping relation extending downward and forward of said panel with their side and lower cut edges exposed to view.
- 50 55 4. A panel simulating in appearance a shingle roof in miniature, said panel comprising a base member formed to provide mounting elements corresponding in shape and arrangement to the exposed areas of the shingles of a shingle roof and inclined generally downward and forward of said base member, and facing elements cut apart from each other and corresponding in shape and size and arrangement to said mounting elements respectively secured on the outer faces of the latter and inclined generally downward and forward of said panel with their side and lower cut edges exposed to view.
- 60 65 5. A panel simulating in appearance a shingle roof in miniature, said panel comprising a base member formed to provide flat mounting elements corresponding in shape and arrangement to the exposed areas of the shingles of a shingle roof with the lower ones of said elements respectively inclined generally downward and forward of said panel from the lower edges of the next superjacent elements, and facing elements cut apart from each other and corresponding in shape and size

and arrangement to said mounting elements respectively secured flat upon the outer faces of the latter and inclined therewith generally downward and forward of said panel with their side and lower cut edges exposed to view.

6. A panel simulating in appearance a shingle roof in miniature, said panel comprising a base member formed to provide flat mounting elements corresponding in shape and arrangement to the exposed areas of the shingles of a shingle roof with the lower ones of said elements respectively inclined generally downward and forward of said panel from the lower edges of the next superjacent elements, and a facing member formed from a single piece of material cut to provide facing elements cut apart from each other and corresponding in shape and size and arrangement to said mounting elements respectively secured flat upon the outer faces of the latter and inclined therewith generally downward and forward of said panel with their side and lower cut edges exposed to view.

7. A panel simulating in appearance a shingle roof in miniature, said panel comprising a base member of sheet material embossed to provide substantially rectangular mounting elements arranged in rows lengthwise of said base member with the elements of each row staggered relative to the elements of the next adjacent row and the upper edges of the elements of each lower row at the lower edges of the elements of the next superjacent row, the elements of each row extending downward and forward of said base member and being spaced apart at their sides with grooves therebetween, and a facing member formed from a single sheet of material cut to provide substantially rectangular facing elements cut apart from each other simulating shingles in appearance and corresponding in shape and size and arrangement to the forward faces of said mounting elements and narrow spacing strips extending between the sides of the facing elements of the respective rows, said facing elements being secured upon the forward faces of said mounting

elements with their lower edges exposed to view and said spacing strips being pressed into said grooves exposing to view the side edges of said facing elements.

- 5 8. A display device simulating in appearance a structure comprising a plurality of elements arranged in overlapping relation with areas and edges thereof exposed to view, said device comprising elements cut apart from each other and 10 corresponding to the exposed areas of said elements of said structure in miniature arranged correspondingly to said areas but in substantially non-overlapping relation with their cut edges exposed to view.
- 15 9. A display device simulating in appearance a structure comprising a plurality of elements arranged in overlapping relation with areas and edges thereof exposed to view, said device comprising a base member formed to provide elements 20 extending therefrom at an inclination to the plane thereof, and facing elements cut apart from each other and corresponding to the exposed areas of said elements of said structure in miniature arranged correspondingly to said areas and secured 25 upon said elements of said base member in substantially non-overlapping relation with their cut edges exposed to view.
- 10 10. A display device simulating in appearance a structure comprising a plurality of elements arranged in overlapping relation with areas and edges thereof exposed to view, said device comprising a base member formed to provide elements 30 extending therefrom at an inclination to the plane thereof, and a facing member formed from a single piece of material cut to provide facing elements cut apart from each other and corresponding to the exposed areas of said elements of said structure in miniature arranged correspondingly to said areas and secured upon said elements of 35 said base member in substantially non-overlapping relation with their cut edges exposed to view.
